to whom it may concern:

Be it known that I, MARK L. SPERRY, of Waterbury, in the county of New Haven and state of Connecticut, have invented a new Design for Oil-Cans; and I do hereby declare the following, when taken in connection with the accompanying drawing and the letters of reference marked thereon, to be a full, clear, and exact description of the same, and which said drawing constitutes part of this specification, i represents a perspective view of an oil-can embodying my design. This invention relates to a design for oil-cans, and the design consists in the configuration of the oil-can as shown in the accompanying illustration. The leading feature of my design consists in a rectangular base G, upon which is supported a circular body, the diameter of which exceeds the length of the said base. The side 20 of the oil-can has a central depression forming a circular base A and a rim B, and around the edge of the can is a bead C, terminating in a neck D, at a point in the periphery of the can diametrically opposite the base. 25

I claim—

In testimony whereof I have signed this specification in the presence of two subscribing witnesses. 30
